ATTORNEY

UNITED STATES PATENT OFFICE.

GEORGE LEROY MILLER, OF SHICKSHINNY, PENNSYLVANIA.

JIG.

Application filed February 20, 1924. Serial No. 694,100.

To all whom it may concern:

Be it known that I, GEORGE L. MILLER, a citizen of the United States, residing at Shickshinny, in the county of Luzerne and State of Pennsylvania, have invented a new and useful Jig, of which the following is a specification.

This invention relates to jigs of the type employed for the separation of minerals or other material by the utilization of the differences in their specific gravities. The form of the invention herein described is particularly well adapted for use in connection with the smaller sizes of anthracite coal for separating the particles of slate therefrom.

The invention has for its objects to improve the general construction and arrangement of the separating mechanism, and the means for controlling the discharge of the slate so that its action will be more directly responsive to conditions existing within the separating box, and will be more positive in its operation than has been the case with jigs as heretofore constructed.

The separation is aided by the circulation of water, which is forced upwardly through the coal by means of a plunger of improved construction, which forms the subject matter of my companion application, Serial

Number 694,101, filed of even date herewith. With the above and other objects in view which will be more fully explained as the description proceeds, the invention consists in various combinations and arrangements of its various parts, which will be more specifically explained in connection with the accompanying drawings, illustrating the invention in its preferred form.

In the drawings:

Figure 1 is a vertical longitudinal section through a jig embodying the invention.

Figure 2 is a horizontal section thereof.

Figure 3 is a fragmentary plan view of the outlet end of the separating box.

Figure 4 is a vertical sectional view of the same taken substantially on the line 4-4 of Figure 3.

Figure 5 is a diagrammatic illustration of the electrical connections for controlling the discharge gate.

Figure 6 is a sectional detail view showing the electric contacts which are controlled by the automatic float.

Figure 7 shows in front elevation the

valved partition through which the water is forced by the plunger into the chamber underneath the separating box.

Figure 8 is a detail sectional view taken on the line 8-8 of Figure 7.

The jig, which is the subject of the present invention, comprises a frame composed of suitably arranged posts 10, connected by longitudinal and transverse bars 11, and supporting a tank 12 having in its upper central portion a separating box 13, into which the coal or other material to be separated is introduced by means of a suitable chute 14. The tank 12 is maintained substantially full of water, and has at one end a chamber 15, which is separated from the remainder of the tank by partitions 16 and 17, and in which reciprocates a plunger 18. The chamber 15 is preferably rectangular, and the plunger 18 has a double connecting rod 19, which is actuated by means of cams 20 secured to a shaft 21, which may be driven by a pulley wheel 22. The water which is used in the tank 12 is used continuously over and over again, except the small portion thereof which is discharged with the coal and slate, and this is replaced by the addition of water through a pipe 23, overhanging the chamber 15. As the plunger reciprocates, it sets up a circulation of water through the chamber 15, so that the water is forced upwardly through numerous perforations 24 in the bottom of the separating box 13, from which it flows outwardly through the cut out portions 25 in the sides of the box. The coal is carried out of the box 13 with the water into the lower ends of the troughs 26, which are arranged, one on each side of the jig, and the coal is delivered therefrom by conveyers 27. The slate is delivered by means hereinafter described to a central trough 28 from which it is carried by a conveyer 29. As the coal settles to the bottom of the water in the troughs 26, the water continues its circulation through chambers 30 back to the chamber 15, the sides of the chambers 30 having portions cut out for this purpose, as shown at 31 and 32.

The operation of the plunger 18 forces the water from the lower part of the chamber 15 through a partition 33, and thence upwardly through the separating box as above described. This partition 33 is made up of

a skeleton frame-work, having a plate 34 in the center connected to the corners thereof by suitable strips 35, between which are comparatively large spaces 36. The passage of the water through the openings 36 is controlled by means of a check valve 37 in the form of a hollow rectangle, with its opening 38 opposite the plate 34. The valve 37 is mounted on bolts 39, which are surrounded by coiled springs 40 adapted to close the valve and prevent a return flow of water during the upward travel of the plunger 18, but permitting the valve to open upon the downward stroke of the plunger. The plunger 18 is also provided with a similar skeleton framework 41 at each end, as shown in Figure 2, and the passage of the water through the plunger is controlled by valves 42 (Figure 1) which are similar to valves 37. Inasmuch as the plunger and valves are not claimed specifically in the present application, but form the subject matter of my companion application above referred to, a further description thereof is deemed unnecessary.

During the operation of the jig, the plunger 18 operates continuously and forces the water upwardly through the perforations 24 in the bottom of the separator box 13, and the coal is held practically in a state of suspension, while the slate and other refuse, being of greater specific gravity, will settle to the bottom of the separator box and work toward the lower end thereof, which is adjacent the partition 43, as shown in Figure 1. The partition 43 is provided with an opening 44 adjacent the bottom of the separator box, and inside this opening is a gate 45 supported by means of screw threaded rods 46, which may be raised or lowered by adjusting the nuts 47, so as to restrict the size of the opening 44, as may be desired. Outside of the opening 44, and spaced a suitable distance from the partition 43, is a second gate 48, which is supported by threaded rods 49, and adjustable vertically by means of nuts 50. This second gate is adapted to regulate the flow of slate through the opening 44, so as to deliver a stream of uniform size. The gate 48 may be adjusted as may be necessary. Outside of the gate 48 is a third gate 51, which is supported by rods 52, these rods being connected at their upper ends to a vertical supporting rod 53 (Figure 5) having at its upper end a head 54, which forms the core of a solenoid 55, through which the gate is automatically operated. The second gate 48 prevents the coal from jamming against the outer gate 51, so that the latter always responds quickly to the solenoid.

The solenoid 55 is adapted to be energized by electric current through the wires 56 and 57, which may be connected to the electric service line by means of the contact

70 fingers 58 and 59 of a three pole switch. The third contact finger of the switch is indicated at 60, and its purpose will shortly be explained. The contact fingers 58, 59 and 60 are connected so as to operate simultaneously, and are normally held open by springs 61 or the like, except when closed by means of an electromagnet 62.

The position of the gate 51 is controlled by the solenoid 55, the operation of which is controlled by means of the switches 58 and 59, and these are in turn controlled by the position of a float 63, located near the lower part of the separator box 13, so that its position is determined by the specific gravity 80 of the material surrounding it. The float 63 is carried at the lower end of a vertical brass rod 64, which is slidably mounted in a bracket 65 and a base 66, which extends across the top of the box 13. Screw threaded rods 67 and 68 are secured at opposite sides of the rod 64 parallel thereto, and have plates 69 of insulating material adjustably secured thereon. Secured to the plates 69, but out of contact with the rods 67 and 68, are contact fingers 70, 71, 72 and 73, respectively. A disk 74 of insulating material is adjustably supported on the rod 64, and carries a copper ring 75 adapted, when the rod 64 is raised, to bridge the contact fingers 70 and 71, while a similar disk 76 is slidably mounted on the lower portion of the rod 64, and carries a copper ring 77 adapted to bridge the contact fingers 72 and 73. The disk 76 is urged upwardly along the rod 64 by an expansile coiled spring 78, but its upward movement relative to the rod is limited by a collar 79, which is secured to the rod. Weights 80 may be attached to the upper part of the rod 64 and these may be changed to adjust the action of the float to the particular conditions under which the jig is operated.

During the operation of the jig, as the particles of coal are continuously agitated by the upward current of water through the separator box, the slate will gradually accumulate around the float 63, so that the latter will be gradually raised. The ring 77, actuated by the coiled spring 78, which is comparatively weak, will first contact with the fingers 72 and 73, and a further accumulation of slate will raise the float and rod 64, and the ring 75 will eventually come in contact with the fingers 70 and 71, as shown in Figure 6. This contact may be only momentary, but it will be sufficient to energize the magnet 62 and close the switch, thus energizing the solenoid 55. The circuit, which energizes the magnet 62, extends through the wire 81 and the coil around the magnet, thence through wires 82 and 83, contact finger 71, ring 75, contact finger 70, wires 84 and 85, contact finger 72, ring 77, contact finger 73 and wire 86 back to the other wire 130

of the line. As soon as the fingers 58 and 59 are closed, the finger 60 is also closed, and a circuit is established through wire 81 and the coil of the magnet 62, thence through wire 82, finger 60, wires 87 and 85, finger 72, ring 77, finger 73 and wire 86 back to the line. Thus, after the magnet 62 has once been energized it will remain energized, although the contact between the ring 75 and the fingers 70 and 71 is broken. The fingers 58 and 59 will therefore remain closed, the solenoid 55 will remain energized, and the gate 51 will remain up while the slate is passing out of the separator box, until the float 63 and rod 64 are lowered sufficiently for the collar 79 to contact with the disk 76, and force the ring 77 out of contact with the fingers 72 and 73. At this point, the circuit through the magnet 62 will be broken, the switch fingers 58, 59 and 60 will be opened, the solenoid will be de-energized, and the gate 51 will be closed.

The above described operation of the gate 51, solenoid 55 and magnet 62 has been based upon the presumption that the flow of water through the separator box 13 has been normal, and the water therein has been maintained at its normal level. In case the flow of water should decrease, or the water level fall below normal, the coal, as well as the slate, would have a tendency to settle to the bottom of the box, and to raise the float 63. In case this should happen, unless some means were provided for preventing it, a considerable amount of coal would escape along with the slate. I have, therefore, provided a supplemental float 88, which is secured to the rod 64 in such a position that when the water is at the normal level, its buoyancy will be added to the buoyancy of the float 63, until the ring 75 reaches the fingers 70 and 71. When, however, the water falls below its normal level, as indicated in Figure 5, the weight of the supplemental float 88 in air will be sufficient to prevent the coal from raising the rod 64 sufficiently to open the gate 51.

The slate, as it is delivered from beneath the gate 51, is directed by an inclined apron 89 into a pocket 90 from which it is carried by the conveyer 29 to any suitable point of discharge. The coal, which is carried through the cut out portions 25 at either side of the separator box, settles to the bottom of the conveyer trough 26, whence it is delivered by the conveyer 27 to a desired point of discharge. Both the conveyer 27 and the conveyer 29 may be actuated by means of a shaft 91, driven by means of sprocket gearing 92, from any suitable source of power. Any preferred conveyer mechanism may be used, but since its specific construction forms no part of the present invention, a more detailed description thereof is believed to be unnecessary.

From the foregoing description, it will be understood that I have provided a jig, the operation of which is entirely automatic, and which will accurately effect the separation of the slate from the coal. The positions of the several gates and the relative positions of the contact rings 75 and 77 may be adjusted according to the character of the coal being separated. Not only will the position of the gate 51 be correctly determined to effect the discharge of the slate unmixed with coal during the normal operation of the jig, but provision has also been made to prevent the escape of any coal with the slate, when, for any reason, the level of the water becomes too low, with a consequent decrease in the flow of the coal from the separator box.

While I have shown and described in considerable detail the distinctive features of my invention, it is to be understood that this is merely for the purpose of illustration, and that various modifications may be made therein without departing from the salient features of the invention, or sacrificing any of the advantages thereof.

What is claimed is:

1. In a jig of the character described, the combination of a separator box having an opening near its bottom for the discharge of the heavier particles which settle by gravity in the bottom of the box, a gate controlling said opening, a solenoid associated with the gate and operable when energized to open said gate, a switch controlling the electric circuit through the solenoid, resilient means normally holding said switch open, an electromagnet operable when energized to close said switch in opposition to said resilient means, a float depending within the box in a position to be raised by an accumulation of the heavier particles in the bottom of the box and having a stem with means thereon for closing the circuit through the magnet coil when the float is raised a predetermined distance, and means associated with the last mentioned means for maintaining a circuit through the magnet coil while the float moves downwardly toward its original position.

2. In a jig of the character described, the combination of a separator box having an opening near its bottom for discharging the heavier particles which accumulate by gravity in the bottom of the box, a gate controlling said opening, a solenoid associated with the gate and operable when energized to open the gate, a switch controlling the electric circuit through the solenoid, resilient means normally holding said switch open, an electromagnet operable when energized to close said switch in opposition to said resilient means, a float depending within the box in a position to be raised by the accumulation of the heavier particles in the bottom

- of the box and having a stem with means thereon for closing a circuit through the magnet coil when the float is raised a predetermined distance, and a switch operable 5 simultaneously with the solenoid switch to establish a branch circuit through the magnet coil which remains closed while the float settles back toward its original position, and after the original circuit through the magnet coil is broken.
3. In a jig of the character described, the combination of a separator box having a discharge opening near its bottom, a gate controlling said opening, a solenoid associated 15 with the gate and operable when energized to open said gate, a switch controlling the electric circuit through the solenoid, resilient means normally holding said switch open, an electromagnet operable when energized to close said switch in opposition to said resilient means, a float depending within the box in a position to be raised by an accumulation of the heavier particles in the bottom of the box, a vertical stem having a 20 float secured to its lower end, a contact ring supported on the stem, a second contact ring slidable on the stem, resilient means urging the slidable contact ring upwardly, a collar secured to the stem and limiting the upward 25 movement of the slidable ring thereon, an electric circuit through the magnet coil, including two pairs of contact fingers adapted to be bridged by the respective contact rings to complete the circuit when the float is 30 raised to a predetermined extent, a branch circuit through the magnet coil, a slidable contact ring including a switch which is closed simultaneously with the closing of the solenoid switch, said branch circuit being 35 operable to maintain the magnet and solenoid active while the float settles back to its original position and after the circuit through the first mentioned contact ring is broken.
4. In a jig of the character described, the combination of a separator box having a discharge opening in its side near the bottom, a vertically slidable gate controlling said opening and having a vertical rod 40 secured thereto and extending upwardly, a solenoid located above the gate and having a core secured to the upper end of the rod so that when the solenoid is energized it will 45 open the gate, a switch controlling the electric circuit through the solenoid, an electromagnet operable when energized to close said switch, means for opening said switch when the electromagnet is de-energized, a float depending within the box in a position 50 to be raised by an accumulation of the heavier particles in the bottom of the box, and having a stem with means thereon for closing a circuit through the magnet coil when the float is raised to a predetermined 55 extent, and means associated with the last 60

mentioned means for maintaining a circuit through the magnet coil while the float moves downwardly toward its original position.

5. In a jig of the character described, the combination of a separator box having a discharge opening in its side near the bottom, a vertically slidable gate for controlling said opening and having a vertical rod secured thereto and extending upwardly, a solenoid 75 located directly above the gate and having a core secured to the upper end of the rod so as to raise the gate when the solenoid is energized, a switch controlling the electric circuit through the solenoid, an electromagnet operable when energized to close said switch, means for opening said switch when the magnet is de-energized, a float depending within the box in a position to be raised by an accumulation of the heavier particles 80 in the bottom of the box and having a stem with means thereon for closing a circuit through the magnet coil when the float is raised to a predetermined extent, and a switch connected to and operable in unison with the solenoid switch to establish a branch circuit through the magnet coil, which is maintained while the float settles back toward its original position, and after 85 the original circuit through the magnet coil is broken.

6. In a jig of the character described, the combination of a separator box having a discharge opening in its side near the bottom, a gate controlling said opening, a solenoid having a core connected to the gate and operable when energized to open the same, a float depending within the box in a position to be raised by an accumulation of the heavier particles in the bottom of the box, means operable by the float when raised to energize the solenoid and open the gate, and a supplemental float secured to the stem of the first mentioned float near the normal water level, and tending to prevent the rise of the float and stem when the water level is lowered.

7. In a jig of the character described, the combination of a separator box, a solenoid, means operable by the solenoid when energized to cause the discharge of slate from the box, a switch controlling the electric circuit through the solenoid, an electromagnet operable when energized to close said switch, means for again opening the switch when the electric magnet is de-energized, a float depending within the box in a position to be raised by an accumulation of the heavier particles in the bottom of the box and having a stem with means thereon for closing a circuit through the magnet coil when the float is raised to a predetermined point, and a switch operable simultaneously with the solenoid switch to establish a branch circuit through the magnet coil,

which remains closed while the float settles back toward its original position, and after the original circuit through the magnet coil is broken.

5 8. In a jig of the character described, the combination of a separator box, a solenoid, means operable by the solenoid when energized to cause the discharge of slate from the box, a switch controlling the electric 10 circuit through the solenoid, an electromagnet operable when energized to close said switch, means for again opening the switch as soon as the electromagnet is de-energized, a float depending within the box in a position 15 to be raised by an accumulation of slate in the bottom of the box, a vertical stem having a float secured to its lower end, a contact ring supported on the stem, a second contact ring slidable on the stem, resilient 20 means urging the slidable contact ring upwardly, a collar secured to the stem and limiting the upward movement of the slid- 25 able ring thereon, an electric circuit through the magnet coil, including two pairs of contact fingers adapted to be bridged by the respective rings to complete the circuit when the float is raised to a predetermined extent, a branch circuit through the magnet coil and slidable contact ring and including a switch 30 which is connected to and operable in unison with the solenoid switch, said branch circuit being operable to maintain the magnet and solenoid active while the float settles back to its original position, and after the circuit 35 through the first mentioned contact ring is broken.

9. In a jig of the character described, the combination of a separator box, a solenoid, means operable by the solenoid when energized to cause the discharge of slate from the box, a switch controlling the electric circuit through the solenoid, an electromagnet operable when energized to close said switch, means for again opening said switch as soon 40 as the electromagnet is de-energized, a float depending within the box in a position to be raised by an accumulation of slate in the bottom of the box and having a stem with means thereon for closing a circuit through 45 the magnet coil when the float is raised to a predetermined extent, means associated with the last mentioned means for maintaining a circuit through the magnet coil while the float moves downwardly toward its 50 original position, and a supplemental float 55 secured to the stem near the normal water level and tending to prevent the rise of the float and stem when the water level becomes lower than normal.

60 10. In a jig of the character described, a separator box having a discharge opening near its bottom for discharging the heavier particles, a float depending within the box near its bottom, a vertical reciprocable stem 65 to which the float is secured, means oper-

able when the float stem is raised to a predetermined extent to cause the discharge of the heavier particles from the box, and a supplemental float secured to the stem near the normal water level and tending to prevent the rise of the float and stem when the water level is lowered. 70

11. In a jig of the character described, the combination of a separator box having a discharge opening in its side, a wall extending downwardly below said opening a vertically slid- 75 able gate inside the box adjacent said opening, a second gate spaced from the side of the box outside the opening and extending below said opening and parallel to the downwardly extending wall to form a downwardly directed passageway, and a third gate outside the second gate and vertically movable to open or close the passageway beneath the second gate. 80

12. In a jig of the character described, the combination of a separator box with an inclined bottom and having a discharge opening in the side adjacent the lowest part of the bottom, a wall extending downwardly below said opening a vertically slid- 90 able gate inside the box adjacent said bottom, means for adjusting said gate vertically to restrict the size of the discharge opening, a second gate spaced from the side of the box outside the opening and extending below said opening and parallel to said downwardly extending wall to form a downwardly directed passageway, means for adjusting said second gate vertically, and a third gate 100 opposite the second gate and vertically movable to open or close the passageway beneath the second gate. 100

13. In a jig of the character described, the combination of a separator box having a discharge opening in the side thereof, a wall extending downwardly below said opening a vertically slid- 105 able gate inside the box adjacent said opening, a second gate spaced from the side of the box outside the opening and extending below said opening and parallel to said downwardly extending wall to form a downwardly directed passageway, a third gate outside the second gate and vertically movable to open or close the passageway 110 beneath the second gate, a float inside the box, and means automatically actuated by the float to open or close the third gate according to the amount of heavier particles 115 in the bottom of the box. 120

14. In a jig of the character described, the combination of a separator box with an inclined bottom and having a discharge opening in the side thereof adjacent the lowest part of the bottom, a wall extending downwardly below said opening a vertically slid- 125 able gate inside the box adjacent said opening, means for adjusting said gate vertically to restrict the size of the opening, a second gate spaced from the side of the box out- 130

side the opening and extending below said opening and parallel to said downwardly extending wall to form a downwardly directed passageway, means for adjusting said second gate vertically, a third gate outside the second gate and movable to open or close the passageway beneath the second gate, a float

inside the box, and means automatically actuated by the float to open or close the third gate according to the amount of heavier particles in the bottom of the box. 10

In testimony that I claim the foregoing as my own, I have hereto affixed my signature.

GEORGE LEROY MILLER.
